CLAIM

The ornamental design for a communications headset, as shown and described.

DESCRIPTION

FIG. 1 is a top, front, right, perspective view of a communications headset showing our new design;

FIG. 2 is a back elevational view taken of FIG. 1 with the boom rotated 45 degrees;

FIG. 3 is a back elevational view taken of FIG. 1;

FIG. 4 is a top plan view thereof;

FIG. 5 is a right elevational view thereof;

FIG. 6 is a front elevational view thereof;

FIG. 7 is a left elevational view thereof;

FIG. 8 is a bottom plan view thereof; and,

FIG. 9 is a back view thereof, the broken line showing the human head is for illustrative purposes only and forms no part of the claimed design.
